UNITED STATES PATENT OFFICE.

WILLIAM S. PLUMMER, OF PHILADELPHIA, PENNSYLVANIA.

DESIGN FOR A CORNER-BRACKET FOR BEDSTEAD-FRAMES.

SPECIFICATION forming part of Design No. 31,560, dated September 26, 1899.

Application filed August 12, 1899. Serial No. 727,075. Term of patent 7 years.

To all whom it may concern:

Be it known that I, WILLIAM S. PLUMMER, a citizen of the United States, residing at Philadelphia, in the county of Philadelphia and State of Pennsylvania, have invented a certain new and useful Design for Corner-Brackets for Bedsteads; and I do hereby declare the following to be a full, clear, and exact description of the invention, such as will enable others skilled in the art to which it appertains to make and use the same.

My invention relates to a certain new and useful design for corner-brackets for bedstead-frames, and is illustrated in the accompanying drawings, wherein—

Figure 1 represents a perspective view of a corner-bracket embodying the design. Fig. 2 represents a plan view thereof, and Fig. 3 represents an end elevation.

Similar letters of reference indicate similar parts throughout the several views.

The top panel *a* of the bracket and the bottom panel *b* are connected by side webs *c*, having a reversely-curved recess, as shown. They are also connected by a rear wall *d*, 25 beyond which extend the upright wings or projections *e*, which taper from above downwardly in such manner as to leave a tapering recess wedge shape in cross-section.

What I claim is—

The design for a corner-bracket for bedstead-frames, substantially as shown and described.

In testimony whereof I affix my signature in presence of two witnesses.

WILLIAM S. PLUMMER.

Witnesses:

FRED. C. MILLER,
BELLA D. BERKHEISER.
